UNITED STATES PATENT OFFICE.

ALFRED P. SEIDELL, OF BLOOMFIELD, NEW JERSEY, ASSIGNOR TO ORANGE LIGHTING FIXTURE MANUFACTURING COMPANY, OF ORANGE, NEW JERSEY, A CORPORATION OF NEW JERSEY.

DESIGN FOR AN ARM FOR ELECTRIC CHANDELIER.

Application filed August 8, 1925. Serial No. 14,346. Term of patent 3½ years.

To all whom it may concern:

Be it known that I, ALFRED P. SEIDELL, a citizen of the United States, residing in the town of Bloomfield, in the county of Essex and State of New Jersey, have invented a new, original, and ornamental Design for an Arm for Electric Chandeliers, of which the following is a specification, reference being had to the accompanying drawing, forming a part thereof.

In the drawing,

The figure is a side view of an arm for electric chandeliers, showing my new design.

I claim:

The ornamental design for an arm for electric chandeliers, as shown.

ALFRED P. SEIDELL.
